SWEATBAND AND METHOD OF MAKING

Abel B. Christiana, Ilion, N. Y.

Application December 19, 1947, Serial No. 792,672

2 Claims. (Cl. 2—181)

1

This invention relates to sweatbands and associated portions of head coverings as hats and the like and methods of associating sweatbands with adjacent portions of head coverings.

An important object of the invention is to provide a novel sweatband, which will substantially prevent the movement of moisture, such as perspiration, by capillary attraction along the stitches, which secure a sweat band to a hat and the like, whereby the moisture will not reach the hat band and damage it or render it unsightly.

Another important object is to accomplish the desirable result just described without the use of adhesives, pads or like layers of material which would add to the wall thickness of the crown adjacent the brim.

Still another important object is to provide a novel association of sweat band and hat or the like, wherein stitches are employed to secure the sweat band to the crown but the stitches do not extend through the wall of the sweat band to the head-engaging surface thereof.

Another major object is to provide a method of associating a sweat band and hat or the like.

Other objects and advantages of the invention will be apparent during the course of the following detailed description of the invention, taken in connection with the accompanying drawing, forming a part of this disclosure, and in which drawing:

Figure 1 is a vertical section through a head covering containing one of the novel sweat bands associated therewith.

Figure 2 is an enlarged fragmentary vertical section of the same.

Figure 3 is a fragmentary plan view of a head covering, with the novel sweat band and a hat band associated therewith.

In the drawing, wherein for the purpose of illustration is shown a preferred embodiment of the invention and wherein similar reference characters designate corresponding parts throughout the several views, the letter A designates a head covering, with the novel sweat band B associated therewith and secured thereto by stitches C.

The head covering A is illustrated as a hat having a crown portion 5 with inner and outer faces 6 and 7 respectively, a brim portion 8 extending from the crown portion 5, and a hat band 9 extending about the portion 5 at outer face 6 of the crown adjacent the juncture of crown and brim portions.

In the example shown, the sweat band B which is preferably of a material substantially impervious to perspiration and the like, such as leather,

2

has a head-contacting face 10 and opposite or crown-contacting face 11 and is, preferably, as thick as a conventional sweat band, except that its lower edge portion may be reduced in thickness as will be described.

The sweat band B is separated in any approved way, such as split longitudinally toward but preferably short of its upper edge 12 so that a longitudinally-extending, downwardly-opening, preferably continuous, compartment or opening 13 is provided extending upwardly from the lower or open edge of the sweat band. This opening 13 which is preferably a slit has its end 14 spaced above the point where the stitches C will be made, as shown in Figure 2.

It will be noted in Figure 2 that the lip 15, which is the lip adjacent the crown 5 is shorter than the lip 16 which is the lip farthest from the crown and that this makes it possible to curl or arch the lip 16 so that it will conceal the opening or slit 13 and the lip 15 and, in addition, there will not be a relatively thick, unsightly bulge as would be the case if the lower end of the sweat band were of the same thickness as the rest of the sweat band.

After separating the sweat band as described, it may be placed within the crown portion 5 with the face 11 of the sweat band in contact with the face 6 of the crown portion, as in Figures 1 and 2, the walls of the opening or compartment separated by moving the outer wall 17 away from the inner or crown-facing wall 18 of the sweat band, and the stitches C made through the wall 18, and as they would be made conventionally, through the crown wall. Thereupon the loose wall being the wall 17 of the sweat band may be dropped into position and there will be a solid, imperforate wall section, free of protruding stitches, between the head of the wearer and the stitches C, as is clear in Figures 2 and 3.

Since the stitches C, which may be of conventional thread used in stitching sweat bands to crowns, do not extend to the face 10 of the sweat band, perspiration cannot reach them, nor be apt to travel along the stitches to the crown and hat band 9 and damage or discolor it.

Due to the fact that materials as adhesives, latex, and the like, or pads are not used, the transverse cross section of crown portion 5 and associated sweat band B is no greater than that of crown portions and associated conventional sweat bands of head coverings.

Various changes may be made to the form of the invention herein shown and described without

departing from the spirit of the invention and scope of the claims.

What is claimed is:

1. In combination with a head covering having a crown portion provided with an inner face and means to connect a sweat band to the crown portion, comprising stitches, a sweat band having a face in contact with said inner face, said sweat band having a head-contacting face, an upper edge, a lower edge, and an opening extending longitudinally of said band with its mouth at said lower edge and its end spaced from said upper edge, with said stitches extending from said crown portion to said opening above the mouth of said opening, said head-contacting face being free of 10 said stitches and said mouth having two lips, with the lip nearest said crown portion being shorter than the other lip, and with the longer lip extending over the edge of said shorter lip.

2. In a method of associating a sweat band with a head covering having a crown and brim, the steps of splitting longitudinally the lowermost portion only of said sweat band to provide two 20 lips; removing a longitudinally-extending section of one lip, whereby one lip is longer than the other 25

lip and extends beyond the shorter lip; positioning said sweat band upon the inner face of said crown with the longer lip outermost and extending beyond said crown; raising the outermost wall 5 of said lowermost portion to expose said slit; stitching said sweat band to said crown; replacing said lowermost portion to conceal said slit and the stitches; and rolling said longer lip toward said brim to conceal the shorter lip.
